CLAIM

The ornamental design for a display mount, substantially as shown and described.

DESCRIPTION

FIG. 1 is a front, bottom, and left side perspective view of a display mount, showing our new design;
FIG. 2 is a top, rear, and right side elevation view thereof;
FIG. 3 is a front elevation view thereof;
FIG. 4 is a right side elevation view thereof;
FIG. 5 is a rear elevation view thereof;
FIG. 6 is a left side elevation view thereof;
FIG. 7 is a top plan view thereof;
FIG. 8 is a bottom plan view thereof; and,
FIG. 9 is another front view thereof, taken from FIG. 4.

1 Claim, 6 Drawing Sheets
